UNITED STATES PATENT OFFICE.

EMIL J. KRAFT, OF RACINE, WISCONSIN, ASSIGNOR TO RACINE RUBBER COMPANY, OF RACINE, WISCONSIN, A CORPORATION OF WISCONSIN.

DESIGN FOR A TIRE.

59,494.

Specification for Design.

Patented Oct. 25, 1921.

Application filed June 15, 1921. Serial No. 477,835. Term of patent 14 years.

To all whom it may concern:

Be it known that I, EMIL J. KRAFT, a citizen of the United States, residing at Racine, in the county of Racine and State of Wisconsin, have invented a new, original, and ornamental Design for Tires, of which the following is a specification, reference being had to the accompanying drawing, forming a part thereof, in which—

Figure 1 is a plan view of a section of a tire embodying the invention and

Fig. 2 is a transverse section on the line 2—2 of Fig. 1.

I claim:

The ornamental design for a tire, as shown.

EMIL J. KRAFT.
